(57) **CLAIM**

The ornamental design for a light emitting shaver as shown and described.

DESCRIPTION

FIG. 1 is a front, top, right perspective view of a light emitting shaver in an illuminated state, showing the new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a front, top, right perspective view of a light emitting shaver in a non-illuminated state, showing the new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

The area of darker stipple shading on the shaver head indicates the lighted region of the shaver head in operation. The broken lines of even length illustrate portions of the shaver and form no part thereof.

The dash-dot-dash broken lines illustrate the boundary of the light emitting shaver and form no part of the claimed design.
